UNITED STATES PATENT OFFICE.

JOHN H. ELWARD, OF STILLWATER, MINNESOTA.

CAR-AXLE BOX.

SPECIFICATION forming part of Letters Patent No. 253,688, dated February 14, 1882.

Application filed December 27, 1881. (No model.)

To all whom it may concern:

Be it known that I, JOHN H. ELWARD, a citizen of the United States of America, residing at Stillwater, in the county of Washington 5 and State of Minnesota, have invented certain new and useful Improvements in Car-Axle Boxes; and I do hereby declare the following to be a full, clear, and exact description of the invention, such as will enable others skilled in 10 the art to which it appertains to make and use the same, reference being had to the accompanying drawings, and to letters or figures of reference marked thereon, which form a part of this specification.

15 Figure 1 is an end view of an axle-box embodying my improvements. Fig. 2 is a side view of the same. Fig. 3 is a longitudinal section, showing also the relations of the box to the axle and the wheel.

20 In the drawings I have shown a sufficient part of the axle and the axle-box to illustrate the essential features of my invention.

Heretofore it has been common to form or 25 cast the end of the axle-box with an inwardly-projecting boss, arranged to bear against the end of the axle to receive the end-thrust and hold the parts in proper relative positions. The boss has generally been made in a single 30 piece, and therefore, as will be readily seen, the movements of the axle result in wearing away the engaging-face of the boss to such an extent as to destroy its efficiency. The boss being thus rendered inoperative, it is necessary to remove that portion of the box carrying it and replace it with a new one, thus entailing 35 much expense, which I obviate by my improved device.

A represents a portion of an ordinary car-axle, and B the wheel thereon. The box out- 40 side of the wheel is shown as being formed of the top C, the bottom D, the side walls, E, the inner walls, F, and the front partial wall, G; but the essential features of my invention may be embodied in axle-boxes of other forms than 45 the one here shown. The side parts are arranged to operate in substantially the ordinary manner as an oil-receptacle.

H H' represent the two parts of the adjustable boss. I have shown them one, H, formed 50 with and connected to a cap-piece or closing-piece, I, for the box, (though it may be formed

separately therefrom and secured to it in any desired way,) and the other, H', formed separately therefrom. The cover or closing-piece I extends from the part G of the front wall to 55 the top of the box. From this outer portion project inwardly pins or guide-pieces h h, either cast with or inserted into said part H. The part H' is provided with a central aperture and eccentric apertures corresponding in number and position to the pins or guide-pieces h. K represents a bolt passing through the cap or closing piece I and the part H of the boss into the opposing movable part, H', engaging with the part I or the surrounding strap by means 60 of its thread. After the bearing-face of the part H' has become worn to such an extent as to prevent it from bearing properly against the axle, it can be moved inward by the bolt and held. Rotation of the part H' is prevented 65 by the pins h. Washers at h² may be used, if desired. In this way the wearing part can be adjusted into any position when such adjustment is made necessary by wear, and it will be seen that even if the part H' should be entirely destroyed by wear or otherwise it renders necessary only a small and simply-constructed piece of metal to be replaced, instead of the much larger and more expensive pieces which must be replaced when use is made of 70 the ordinary devices.

The cap or closing piece is supported by means of a surrounding strap or yoke having the cross-piece L and side pieces, L'. These side pieces are pivoted at l in the side walls 85 of the box by means of bolts. The strap or yoke L L' is rigidly secured to the cap or covering piece I, not only by means of the central adjusting-bolt, K, but also by means of supplemental bolts at or near the side of the box. 90

When it is desired to have access to the interior of the box the latter may be opened by throwing upward the strap L L' and the cap or covering piece I upon the bolts at l as centers. When the parts are in the position shown 95 in Fig. 3 the thrust of the axle, it will be seen, is in such direction relative to the position of the movable parts of the box that it (said thrust) will not tend to throw up the cover; but, if desired, fastening devices or locks of any 100 suitable character may be employed to prevent the cover from being removed from the box.

What I claim is—

1. The combination, with the car-axle box and the axle of the bearing-piece H', situated entirely inside of the walls of the box, the adjusting screw or bolt K, which supports the bearing-piece, and the pins h h, which hold the bearing-piece in proper position, substantially as set forth.
2. The combination, with the axle and the box surrounding its end, of the boss H, carried by the end piece of said box, the adjustable bearing-piece H', and the devices which prevent it from rotating, substantially as set forth.

3. The combination, with the box, the axle, the cover I, and the swinging pivoted strap L L', of the adjustable bearing-piece H' and the bolt K, passing through said strap and cover and adapted to adjust the bearing-piece H', substantially as set forth.

In testimony whereof I affix my signature in presence of two witnesses.

JOHN H. ELWARD.
